SELF-CLEANING WELL LINER
AND THE LIKE

Freeman E. Fairfield, Long Beach, Calif.

Application May 19, 1934, Serial No. 726,585

1 Claim. (Cl. 166—5)

This invention relates to oil well equipment and particularly pertains to self-cleaning liners for oil wells and the like.

In the operation of oil wells, and other types of wells, it is often the practice to provide a liner which is a tubular metal structure adapted to retain the well bore in proper form, and which is formed with perforations through which fluid from the earth formation being penetrated may flow into the well. Incident to this operation the fluids will tend to carry silt and other earthy material through the perforations and will tend to clog the same. This is especially true due to the common practice at the present time of forming such perforations, which consists in cutting a longitudinally extending slot through the metal wall by the use of a circular metal saw. The result of such a cutting operation is that while the sides of the slotted opening will be parallel and straight, the kerf formed by the cutting tool at the ends of the slot will be inclined inwardly. The lower inclined face presents a barrier which tends to cause an accumulation of silt and other finely divided material at the bottom 20 of the slot and tends to build up this accumulation within the slot to clog the same. It is the principal object of the present invention to provide a well liner and the like structure with slots which prevent clogging, and tend to insure that the flow of fluid through the slots will move the material which might otherwise accumulate therein, and maintain the slots in a free and unclogged condition throughout their length.

The present invention contemplates the formation of slots through the wall of a well liner or the like, which is characterized by the fact that at one or both ends thereof the width of the slot is increased whereby a fluid will have more easy access to the slot and will flow readily therethrough.

The invention is illustrated by way of example in the accompanying drawing in which:

Figure 1 is a view showing a fragmentary portion of a well liner with a series of slots formed therein.

Fig. 2 is an enlarged view in elevation showing a preferred form of slot with an enlarged opening at its lower end and indicating in dotted lines the portion of the original slot which was removed.

Fig. 3 is a view in longitudinal section and elevation showing other details of the slot construction.

Fig. 4 is a fragmentary view in transverse sec-

tion as seen on the line 4—4 of Fig. 2, and as showing the undercut side walls of the slot.

Referring more particularly to the drawing, 10 indicates a tubular metal member, such for example as an oil well liner, the wall of which is formed with perforations 11. As previously explained, these perforations are formed through the wall of the tubular member to permit gases, oil, and other fluids to flow from the earth formation into the well liner. It is common practice to form these members in the shape of longitudinal slots arranged in circumferentially extending rows around the liner and for any desired length therealong. These slots are usually formed with parallel side walls 12 and 13, the 15 opposite ends of which terminate in inclined faces 14, representing a segment of the circumferential contour of a cutting saw with which they are made. Such a face is shown in section in Fig. 3 of the drawing. It is more desirable to form the 20 end faces of the slots either square or undercut toward the inner face of the wall. In common practice, however, the machine work required to thus perforate the liner is impracticable. The side faces 12 and 13 are, however, undercut, as 25 indicated by dotted lines in Fig. 2 of the drawing, and as more particularly shown in the fragmentary section Figure 4.

The appearance of the lower end of the usual slotted perforation is indicated by dotted lines in 30 Fig. 2 of the drawing. In a slot of this character it will be seen that the openings are uniform in width throughout the length of the slot, and that the lower edge of the slot is tapered downwardly and outwardly so that silt might accumulate 35 upon it, and finally cause a deposit of silt and other finely divided material from the well to pack in the slot to completely or partially clog the same. Applicant contemplates changing the formation of the slot at one or both of its ends 40 whereby the end face of the slot will be straight or might be undercut toward the inside of the liner. This is preferably accomplished by drilling a hole 15 at one or both ends of the slot, the diameter of the hole being greater in width than 45 the diameter of the slot so that a passageway will be formed through the casing wall to accommodate a larger volume of liquid and to have a free and straight flow, since the end of the slot will then be straight as indicated at 17, or as indicated by dotted lines 18, both shown in Fig. 3. It 50 will be understood, of course, that the slot may be enlarged by other methods than here shown, such as by punching, and that if desired the enlarged portion might be of another shape than sub- 55

stantially circular as indicated in the drawing. In any event, however, the lower end of the slot will be of relatively large cross-section as compared with the body of the slot, and there will 5 not be the tendency or probability that finely divided material will accumulate and build up from the lower end of the slot to partially fill the slot and obstruct the passage therethrough.

It will also be evident that in the event silt 10 should become bridged across the restricted portion of the slot the eroding action of the fluid which passes through the relatively wide portion 15 of the slot at the lower end thereof, or at opposite ends thereof, as indicated in Fig. 1, at 19, will eventually wear away the bridged material 20 and clear the slot. The result will be that the slots as here shown will be self-cleaning at all times and will insure that the well liner may be maintained in its operative position without clogging and without retarding the amount of fluid going through the slot.

It will thus be seen that the oil well liner and the like here disclosed, while decidedly simple in its construction, insures an operation which will

maintain flow of fluid through the wall of the liner without material obstruction, and will maintain the slots in a clear and clean condition.

While I have shown the preferred form of my invention, as now known to me, it will be understood that various changes may be made in the combination, construction, and arrangement of parts, by those skilled in the art, without departing from the spirit of the invention as claimed. 10

Having thus described my invention, what I claim and desire to secure by Letters Patent is:

A liner for well casings and the like, comprising a tubular member, said tubular member having perforations through its wall, the perforations being formed by drilled openings spaced apart a distance represented by a plurality of its diameter and connected by a slotted opening having straight side walls spaced apart a distance less than the diameter of the circular end openings, 15 said straight side walls lying upon opposite divergent planes from the outside of the tubing toward the inside. 20
